(57) CLAIM

The ornamental design for an apple shaped carabiner, as shown and described.

DESCRIPTION

FIG. 1 is a top plan view of our new design for an apple shaped carabiner, with the bottom view being a mirror image;

FIG. 2 is a left side elevation view of FIG. 1.

FIG. 3 is a right side elevation view of FIG. 1.

FIG. 4 is a rear side elevation view of FIG. 1.

FIG. 5 is a front side elevation view of FIG. 1.

FIG. 6 is a top perspective view of FIG. 1.

FIG. 7 is a top plan view of a second embodiment of the design shown in FIG. 1 with the bottom view being a mirror image thereof;

FIG. 8 is a left side elevation view of FIG. 7.

FIG. 9 is a right side elevation view of FIG. 7.

FIG. 10 is a rear side elevation view of FIG. 7.

FIG. 11 is a front side elevation view of FIG. 7; and, FIG. 12 is a top perspective view of FIG. 7.
